UNITED STATES PATENT OFFICE.

LUDWIK MARSZALEK, OF PASSAIC, NEW JERSEY.

RAILROAD-SWITCH.

1,350,373.

Specification of Letters Patent. Patented Aug. 24, 1920.

Application filed May 8, 1920. Serial No. 379,864.

To all whom it may concern:

Be it known that I, LUDWIK MARSZALEK, a citizen of the Republic of Poland, residing at Passaic, in the county of Passaic and 5 State of New Jersey, have invented new and useful Improvements in Railroad-Switches, of which the following is a specification.

This invention relates to improvements in switch operating mechanisms and has for 10 an object the provision of means actuated by an approaching car or train for automatically throwing the switch.

Another object is the provision of means controlled by a car or train, whereby the 15 switch points may be moved either to close the track of the main line or to close the siding track, irrespective of the previous position of said switch points.

Another object is the provision of means 20 controlled by a car or train for resetting the switch or for moving the points in either direction, after the passage of the car or train, so as to open or close either the main track or siding for the convenience of a car 25 or train following.

With the above and other objects in view, the invention further includes the following novel features and details of construction, to be hereinafter more fully described, 30 illustrated in the accompanying drawings and pointed out in the claims hereto appended.

In the drawings:—

Figure 1 is a plan view of a section of a 35 railway track and switch, showing the application of the invention.

Fig. 2 is a transverse section taken approximately on a line with the switch setting mechanism and showing the train carrying device for operating the same.

Fig. 3 is a fragmentary section taken longitudinally of this end of the track and also showing the train device.

Fig. 4 is a transverse section taken on a 45 line with the switch resetting mechanism.

Fig. 5 is a fragmentary section taken longitudinally of the track and showing the manner of the engagement of the track device with the resetting mechanism.

Fig. 6 is a detail perspective of the T-shaped lever of the switch setting mechanism.

Fig. 7 is a similar view of the lever engaged by the train device.

Fig. 8 is a sectional view of the train device taken at right angles of Fig. 3.

Referring to the drawings in detail, wherein like characters of reference denote corresponding parts, the numeral 10 indicates the rails of the main track and 11 the 60 rails of the siding, while the switch points are indicated by the numeral 12.

Located in the advance of the switch is a mechanism to be hereinafter referred to as the switch setting mechanism, indicated in 65 its entirety by the numeral 13, while at the opposite end of the switch and at a suitable distance therefrom is a mechanism to be hereinafter referred to as the switch resetting mechanism and indicated in its en- 70 tirety by the numeral 14.

The switch setting mechanism 13 includes a transversely disposed slideable rack bar 15, which is located beneath the track and preferably to one side thereof and it is shown 75 as operating within the casing or housing 16. The rack bar 15 is provided with a downwardly extending right angular portion 17, which has pivotally connected to its lower extremity a link 18. This link is also 80 pivotally connected to the lower end of a substantially T-shaped lever 19, the latter being pivotally mounted as indicated at 20 between the rails to the main track. The laterally extending portions of the T-shaped 85 lever 19, provide shoulders 21 upon their upper edges for engagement with downwardly extending arms 22, which are carried by levers 23 located between the rails of the track and hereinafter referred to as 90 track devices. One of these track devices is located upon opposite sides of the pivot 20 of the lever 19, lying substantially parallel to one another and having their ends remote from the arms 22, pivotally secured to 95 the roadbed between the rails as indicated at 24. The track devices 23 are also connected to the casing or housing 16 by means of links 25, so that a downward pressure on either of the track devices will move the 100 T-shaped lever 19 upon its pivot and through the medium of the link 18 will move the rack bar 15 transversely of the track.

The resetting mechanism 14, which is located beyond the switch also includes a transversely movable rack bar 26, which like the rack bar 15 is provided with a downwardly extending arm 27. Pivotally secured to the arm 27 is a link 28 and this 110 link is in turn pivotally secured to the lower end of a T-shaped lever 29, which is sub-

stantially similar to the lever 19 previously described and like this lever is pivotally mounted as shown at 30 between the rails of the track. Pivotally secured to the laterally extending portions 31 of the lever 29, 5 is a substantially L-shaped link 32, the latter extending outwardly beyond the sides of the track and being pivotally mounted between the walls of the casing or housing 33, 10 which also receives the lever 29 and which extends transversely of both the main track and the siding.

Pivotally mounted adjacent one of the rails of the main track 10, as indicated at 15 34, is one end of the lever 35, which will also be hereinafter referred to as a track device, while extending from this lever within the casing or housing 33 and connected to one of the L-shaped links 32, is a bar 20 36. A downward pressure of this bar by the wheels of the car passing over the main track will depress the track device, the lever 35 and swing the lever 29 upon its pivot to slide the rack bar in one direction. Pivotally mounted adjacent one of the rails of 25 the siding 11 as shown at 37, is a lever 38, the latter being also provided with a downwardly extending bar 39 for connection with the other L-shaped link 32 and providing an additional track device for engagement 30 by the wheels of the car passing over the rails of the siding, so as to rock the lever 29 and move the rack bar 26 in an opposite direction.

35 Mounted in suitable bearings 40 and disposed longitudinally of the track is a rock shaft 41, the latter being provided at each end with a toothed segment 42 for engagement with the teeth formed in the upper 40 edge of the rack bars 15 and 26, so that a movement of one rack bar will impart a like movement to the other rack bar. The rock shaft 41 is provided with a crank 43 and this crank is connected through the medium of a link 44, with the bar 45 which is in turn connected with each of the switch points 12. By this means the operation of the rock shaft 41 will move the switch points 12 upon their pivots.

50 For the purpose of selectively actuating the track device 23, there is provided a train carried device 46. This device includes a pair of oppositely movable vertical slidable roller carrying members 47, the rollers 48 of 55 which are so spaced as to engage one of the track devices 23. The members 47 are provided upon their opposed faces with teeth 49, which are engaged by toothed segments 50 carried by a transversely extending shaft 51. This shaft is actuated through the medium of suitable connections from a convenient point of the car and when rotated will move the members 47 vertically in opposite directions so as to bring either 60 one of said members into position for en-

gagement with its respective track device. By this means the switch points may be operated to close either the main line or the siding by moving the proper roller 48 into position for engagement with one of the track devices 23. This will rock the T-shaped lever 19 upon its pivot and will, through the medium of the rack bar 15, rock the shaft 41. This shaft will in turn actuate the rack bar 26 and rock the lever 29 upon 75 its pivot. This movement of the lever 29 will raise the track device 35 upon the side of the track opposite to the track devices 23 of the switch setting mechanism, so that the wheels of the car after passing over the 80 switch will depress the said track device 35 and reset the switch in its original position.

The invention is susceptible to various changes in its form, proportions and manual details of construction and the right is 85 herein reserved to make such changes as properly fall within the scope of the claims.

Having described the invention, what is claimed is:—

1. The combination with a railway switch, 90 of a car actuated switch setting mechanism located in advance of the switch and including a rock shaft disposed longitudinally of the track, means for connecting the switch points to the rock shaft, whereby operation of the latter will move the switch points to set the switch, a transversely movable rack bar for operating the rock shaft, a pivoted T-shaped lever located between the rails of the track, spaced parallel levers 95 having one of their ends pivotally secured between the rails and extending longitudinally of the latter, right angularly disposed downwardly extending arms rigidly secured to said levers and engageable in notches provided in the T-shaped bar and means located beyond the opposite end of the switch for returning the latter to normal position.

2. The combination with a railway switch, 110 of a car actuated switch setting mechanism located in advance of the switch and including a rock shaft disposed longitudinally of the track, means for connecting the switch points to the rock shaft, whereby operation of the latter will move the switch points, a 115 transversely movable rack bar for operating the rock shaft, a pivoted T-shaped lever located between the rails of the track and pivotally mounted car operated levers disposed longitudinally of the track and engageable 120 upon the opposite sides of the pivot of the T-shaped lever for rocking the same in either direction, and means located beyond the opposite end of the switch for returning the latter to normal position.

3. The combination with a railway switch, 125 of transversely movable rack bars disposed at opposite ends of the switch, a T-shaped lever mounted for pivotal movement between the rails of the track at each end of 130

the switch and operatively connected to the rack bars, car actuating means located upon opposite sides of each of the T-shaped levers for rocking the same upon their pivots to move the rack bars in either direction, means for connecting each of the track bars to insure their simultaneous movement,

means operatively connecting the rack bar and a car carried device for selectively operating either of the car actuated means to move the switch points in either direction from opposite sides of the switch.

In testimony whereof I affix my signature.
LUDWIK MARSZALEK.
